**PHOSPHATE-FREE CARBOXYLATE-SULFATE
DETERGENTS**

This is a division of application Ser. No. 259,924, 5 filed June 5, 1972, now U.S. Pat. No. 3,843,707.

BACKGROUND OF THE INVENTION

This application is directed to detergent active materials which may be incorporated into detergent formulations which are capable of being used for heavy duty laundering without the presence of either eutrophication-causing or highly alkaline materials which are harmful to human tissue. In addition, these detergent active materials possess other virtues, the combination of which is unique in the detergent area. Thus the compounds are both aerobically and microaerophilically biodegradable and possess low (exceptionally low with certain species of the compounds) fish toxicity properties. 10

As is well known, in the United States accelerated concern for the protection of the environment has resulted in efforts by the concerned branches of Government and the detergent industry to eliminate phosphate builders from detergent compositions because of the fear of suspected eutrophication believed to be caused by the phosphates in the currently used detergent formulations. The precipitous introduction and marketing of many hurriedly formulated phosphatefree compositions has, however, raised the spectre of the cure being possibly worse than the illness due to the caustic nature of many of the formulations. The necessity of including some builder in the formulations as a replacement for the phosphates in order to achieve sufficient detergency has resulted in these formulations being compounded with such materials as meta-silicates and carbonates making the danger of skin, eye, and mucous membrane damage to persons who use the formulations a substantial one. Thus the Federal government has required that several of the new detergent 25 formulations be labeled as hazardous substances and the Surgeon General of the United States has recently recommended that housewives continue to use phosphate-containing detergents for the present as being "the lesser of evils". 30

In addition to the corrosive properties of many of the new detergent formulations, despite claims to the contrary, many of them have not proved to be effective replacements for conventional heavy duty detergents in terms of their ability to remove soil from fabrics and provide clean-appearing clothes, etc. 45

An additional problem with most conventional detergents and which exists as well with most of the newly introduced "nonphosphate" detergent compositions is the fact that while they may be aerobically biodegradable with secondary disposal plants, they are not easily degradable under "microaerophilic" conditions such as are encountered in areas where septic tanks and cesspools provide the means of sewage disposal. This results in substantial quantities of undegraded surface-active materials being discharged into water sources and has resulted in certain areas in Government bans on all laundering agents except for soap. 50

There exists, therefore, a pressing need for detergent-active materials which may be compounded without phosphate builders and without caustic builders, which are biodegradable and are degradable under conditions encountered in septic tanks and cesspools and which

will have minimal effect on marine organisms if discharged by design or accident into rivers and lakes, etc. Thus the detergent actives should not exhibit high toxicity to fish, etc. 55

PRIOR ART

U.S. Pat. No. 3,086,043 discloses as surface active materials compounds of the formula

in which R is alkenyl of 8 to 20 carbons (preferably branched), R' is lower alkyl of 1 to 4 carbon atoms or hydrogen, x is 0 to 3, and Z is a salt forming cation. The compounds are formed by reacting a hydroxy-containing sulfonate such as sodium isethionate with alkenyl succinic anhydride. 15

SUMMARY OF THE INVENTION

Detergent active materials capable of being formulated into compositions which are suitable for heavy duty laundering in the absence of phosphate builders or such highly caustic building materials as carbonates, meta-silicates, etc., are provided. The detergent active materials are easily biodegraded, both aerobically and microaerophilically, and certain compounds display surprisingly low toxicity to marine organisms. The detergent actives are sulfated glycol or polyglycol half esters of alkyl or alkenyl succinic acids or water-soluble salts thereof, wherein the alkyl or alkenyl group contains from about 14 to about 22 carbon atoms and the glycol moiety of the ester contains from 1 to 4 units of 20 to 4 carbon atoms and the sulfate group is terminally attached to the glycol or polyglycol chain. The preferred glycol units contain two carbon atoms. 30

While the compounds disclosed above have good detergency and low fish toxicity levels consonant with 40 most of the available detergents such as linear alkylbenzene sulfonate, a preferred embodiment of the invention having, along with excellent detergency, surprisingly low fish toxicity levels is represented by the class of compounds of the following formula:

in which R₁ and R₂ are substantially linear saturated or unsaturated aliphatic groups of 2 to 19 carbon atoms, 55 R₃ is alkylene of 2 to 4 carbon atoms, u, v, x and y are 0 or 1, z is an integer 1 to 4, M is H or a water-soluble salt-forming cation, the sum of the carbon atoms in R₁ and R₂ is from about 13 to 21 carbon atoms, the sum of unsaturated sites in R₁ and R₂ is 0 to 1, the sum of u and v is 1, the sum of x and y is 1, and the sum of u and x is 1. 60

Thus the preferred compounds are preferably derived from hydrocarbyl succinic anhydrides wherein the attachment of the succinic moiety to the hydrocarbyl group is at carbon atoms other than the 1 and 2 carbon atoms of the hydrocarbyl chain. Such attachment as used in this application is defined as "central attachment". Bonding at carbon atoms 1 and 2 of the

hydrocarbyl group is defined as "end attachment".

In an additional preferred embodiment z is an integer of 1 to 3, preferably 1 to 2, most preferably 2, and R_3 is ethylene. It is further preferred that the sum of carbon atoms in R_1 and R_2 is from 15 to 17. Thus, the preferred materials are sulfate salts of half esters produced by reacting ethylene glycol or diethylene glycol with an alkyl or alkenyl succinic anhydride having 16 to 18 carbon atoms in the side chain. The diethylene glycol derivative is most preferred as is the alkyl derivative.

The hydrocarbyl radicals illustrated in the formula by R_1R_2CH- include such groups as tetradecyl, pentadecyl, hexadecyl, heneicosyl, docosyl, tetradecenyl, pentadecenyl, hexadecenyl, heneicosenyl and docosenyl.

Typical compounds illustrating R_1 , R_2 and R_3 are listed as follows:

R_1	R_2	R_3	Z	M
ethyl	undecyl	ethylene	1	Na
propyl	undecenyl	1,2-propylene	2	K
butenyl	tridecyl	1,3-propylene	1	NH_4
pentyl	dodecyl	1,4-butylene	1	Na
hexenyl	tetradecyl	1,2-propylene	3	Na
heptyl	heptyl	ethylene	4	K
decenyl	undecyl	ethylene	1	Na
propyl	heptadecyl	ethylene	2	Na
nonyl	octyl	ethylene	2	Na
octyl	octyl	ethylene	1	Na
heptyl	octenyl	1,2-butylene	1	K

DESCRIPTION OF THE PREFERRED EMBODIMENTS

The salt-forming cation M may be any of numerous materials such as alkali metal, alkaline earth metal, ammonium, or various organic cations. Examples of suitable organic cations include nitrogen-containing organic cations such as diethanolammonium and triethanolammonium cations. The alkali metal cations are preferred, and sodium ions are particularly preferred.

The alkyl and alkenyl groups which are attached to the succinic moiety may be branched or linear, although the substantially linear materials are preferred. By substantially linear is meant that the presence of a random methyl group, for example, somewhere on the chain will not be detrimental to their ability to be degraded. The preferred alkyl groups thus include the linear alkyl from tetradecyl to docosyl and the alkenyl groups will likewise be the linear materials from tetradecenyl to docosenyl.

The succinic anhydride precursors are preferably derived by the alkylation of maleic anhydride with a monoolefin to form alkenyl succinic anhydride followed in the case of the alkyl substituted materials by hydrogenation. The olefins may be derived from any source, examples being those derived from the cracking of waxes (alpha olefins) or those derived by dehydrogenation or halogenation-dehydrohalogenation of appropriate paraffin fractions. From a commercial standpoint olefins derived by various dehydrogenation processes are preferred.

The reaction of olefin with maleic anhydride is performed as conventionally described in the art by contacting the anhydride with at least an equimolar amount, preferably an excess of olefin, usually at elevated temperatures, to form the desired anhydride.

The alkenyl materials may be converted to alkyl succinic anhydrides by conventional hydrogenation techniques. Alternatively and preferably, the hydrogenation is carried out with the half ester. Hydrogenation may thus be carried out in the presence of conventional catalysts such as platinum, platinum on inert supports, palladium, etc.

The alkenyl or alkyl succinic anhydride is reacted with an appropriate quantity of a lower glycol or lower polyglycol to yield the half ester. An approximately stoichiometric amount of the glycol or polyglycol will cleave the anhydride ring to form the desired compound having a free carboxyl group and a hydroxyl group on the glycol or polyglycol portion of the molecule. The use of an excess of the glycol is preferred.

Sulfation of the glycol substituted half ester to produce the acid precursor of the compound is accomplished by any appropriate sulfation method, such as oleum, sulfuric acid, or chlorosulfonic acid.

The mixed carboxylic, sulfuric acid produced is reacted with an appropriate base in order to give the detergent-active salt which then may be compounded to form the desired detergent composition.

The preferred detergents contain one or two ethylene glycol units. Fish show markedly high tolerance to these materials. In addition, the preferred compounds contain a succinic moiety which is centrally attached on the hydrocarbyl chain.

The glycols which are precursors of the preferred compounds are represented by the formula

in which Y is H or a water-soluble salt-forming cation, p is 1 to 4, R_1 and R_2 are substantially linear saturated or unsaturated, unsubstituted aliphatic groups of 2 to 19 carbon atoms, R_3 is alkylene of 2 to 4 carbon atoms, u , v , x and y are 0 or 1, the sum of the carbon atoms in R_1 and R_2 is from 13 to 21 carbon atoms, the sum of the unsaturated sites in R_1 and R_2 is 0 to 1, the sum of u and v is 1, the sum of x and y is 1, and the sum of u and x is 1. In the preferred precursor the sum of the carbon atoms in R_1 and R_2 is 15-17, and p is 1 to 2, preferably 2; and R_1 and R_2 are alkyl.

The following examples illustrate the preparation of the detergent active materials of this invention.

EXAMPLE 1

Preparation of Octadecenyl Succinic Anhydride

9.08 Kg. (36.0 moles) of isomerized linear octadecene and 1.96 kg. (20.0 moles) of maleic anhydride were charged to a pressure vessel. The stirred mixture was heated under 30 psi of nitrogen for 6 hours at 230°C. After the mixture cooled, it was transferred to a distillation apparatus and distilled, boiling point 430°-450°F. at 0.1-0.2 mm/Hg. A 93% yield of octadecenyl succinic anhydride was obtained. The product had the following isomer distribution as determined by vapor phase chromatography:

Isomer	Percent
2-attachment	4.5
3-attachment	6.4
4-attachment	11.1
5-attachment	18.5
6,7,8,9-attachment	59.3

This represents a product having 95.5% central attachment.

EXAMPLE 2

Hydrogenation of Octadecenyl Succinic Anhydride

20 G. (0.057 moles) of octadecenyl succinic anhydride, 114 g. of n-hexane and 1 g. of 5% palladium on carbon were charged to a pressure vessel. The mixture was stirred and heated to 50°C. The initial hydrogen pressure was 60 psi. When the pressure dropped to 50-50 psi, the system was represented to 60 psi. This process was repeated until the hydrogen uptake essentially ceased. The mixture was filtered and the hexane was evaporated. 19.7 G. (98.5% yield) of crude octadecyl succinic anhydride was recovered.

EXAMPLE 3

Preparation of Diethylene Glycol Half Ester of Octadecenyl Succinic Acid

238.0 G. of diethylene glycol (2.25 moles) and 26.3 g. of a linear octadecenyl succinic anhydride (0.0747 mole) prepared as in Example 1 was placed in a vessel and stirred and heated rapidly to 150°-160°C. The solution was maintained at that temperature for 1 hour, then it was cooled to room temperature. A 250-ml. portion of ether was added, and the layers were separated. Then 250 ml. of ether and 125 ml. of water were added to the glycol layer. After extraction, the layers were separated.

Each of the ether layers was extracted three times with about 100 ml. portions of water. The ether layers were combined, dried over sodium sulfate, filtered and evaporated to give 34.1 g. of product. This represented a 99% yield of the diethylene glycol half ester.

EXAMPLE 4

Preparation of Ethylene Glycol Half Ester of Octadecenyl Succinic Anhydride

The procedure of Example 3 was repeated with the exception that 177 g. of ethylene glycol (2.86 moles) and 25.0 g. of octadecenyl succinic anhydride (0.0714 mole) were employed. The yield of product was 95%.

EXAMPLE 5

Hydrogenation of Diethylene Glycol Half Ester of Octadecenyl Succinic Anhydride

9.12 G. (0.02 mole) of a diethylene glycol half ester of octadecenyl succinic acid was dissolved in 42 ml. of n-hexane in a hydrogenation vessel. 1 g. of 5% palladium on carbon was added. The mixture was magnetically stirred and heated in a 50°C. water bath. The initial hydrogen pressure was 60 psi. When the pressure dropped to 30-40 psi, the system was repressured to 60 psi. This process was repeated until the theoretical hydrogen uptake was obtained. The mixture was then filtered and the hexane was evaporated. 14.9 g. (99% yield) of diethylene glycol half ester of octadecenyl succinic acid was recovered. Infrared and nuclear mag-

netic resonance analysis were consistent with the assigned structure and showed that the product was completely saturated.

EXAMPLE 6

Sulfation of the Diethylene Glycol Half Ester of Octadecyl Succinic Acid

2.13 G. (0.00465 mole) of the diethylene glycol half ester of octadecyl succinic acid was dissolved in 100 ml. of dry ether. A 4.44 g. portion (0.0381 mole) of chlorosulfonic acid was added dropwise at a rapid rate. The temperature of the reaction mixture was kept at 10°-15°C. during the addition of the acid. When all of the acid was added, the cooling bath was removed, and the solution was allowed to warm to room temperature over a period of 20-30 minutes.

Sufficient 0.5 N NaOH was added to about 75 ml of water to bring the pH to 11-12. The solution was cooled to 5°-10°C., and the pH was maintained between 8 and 12 by alternate addition of the acid-containing ether solution and 0.5 N NaOH. At a final pH of 8.5, the mixture was partially evaporated to remove ether. The remaining solution was diluted to a known volume. An aliquot was taken for a Hyamine titration, and the amount of active sulfate was determined. The yield of disodium salt of sulfated diethylene glycol half ester of octadecyl succinic acid was 87%.

(1) A blend of approximately equal amounts of each isomer.

(2) A blend having a ratio of 30:40:30 for isomers of increasing molecular weight, respectively.

(3) A blend having a ratio of 26:29:27:18 for isomers of increasing molecular weight, respectively.

EXAMPLE 37

Drying of Disodium Salt of the Half Ester of C₁₆-C₁₈ Alkyl Succinic Acid

A portion of disodium salt of the half ester of C₁₆-C₁₈ alkyl succinic acid was dried on a small scale drum dryer under 35 lbs. of steam absolute (about 125°C.). The product was crushed and screened to give a product which was a free-flowing white powder when dry.

The sulfation products contain varying amounts of by-products in the range of about 1 to 20%. The alkene derivatives have the greater quantity of by-products, about 10 to 20%, whereas the alkyl derivatives have lesser amounts, about 1 to 10%. These by-products may be removed by various purification processes such as extraction, chromatography, etc., but in the present examples they were left in the products because these by-products will normally be present in commercial materials made in accordance with this invention. Consequently, detergency and toxicity measurements reported herein are representative of potential commercial products. Each product was analyzed for detergent active material by the method of House and Darragh, *Anal. Chem.*, 26, 1492 (1954). Test samples were prepared for fish toxicity measurements and for detergency effectiveness using the previously determined surface active values for determining test concentrations.

Detergency of the compounds of the present invention is demonstrated by a miniature Terg-O-Tometer test. In this test the effectiveness of the detergents is measured by their ability to remove natural sebum soil from cotton cloth. By this method, small swatches of cloth, soiled by rubbing over face and neck, are washed with test solutions of detergents in a miniature laboratory washer. The washer employed is so constructed that two standard formulations and two test formulations can be used to wash different parts of the same soiled swatch. This arrangement ensures that all formulations are working on identical soil. The quantity of soil removed by this washing procedure is determined by measuring the reflectances of the new cloth, the soiled cloth, and the washed cloth, the results being expressed as per cent soil removal. Because of variations in degree and type of soiling, in water and in cloth, and other unknown variables, the art has developed the method of using relative detergency ratings for comparing detergent effectiveness.

The relative detergency ratings are obtained by comparing and correlating the per cent soil removal results from solutions containing the detergents being tested with the results from two defined standard solutions. The two standard solutions are selected to represent a detergent system exhibiting relatively high detergency characteristics and a system exhibiting relatively low detergency characteristics. The systems are assigned detergency ratings of 6.3 and 2.2, respectively.

By washing portions of each soiled cloth with the standardized solutions, as well as with two test solu-

tions, the results can be accurately correlated. The two standard solutions are identical in formulation but are employed at different hardnesses.

Standard Solution Formulation		Weight %
Ingredient		
Linear Alkylbenzene sulfonate (LAS)		20
Sodium tripolyphosphate		40
Water		8
Sodium Sulfate		24
Sodium Silicate		7
Carboxymethylcellulose		1

The standard exhibiting high detergency characteristics (Control B) is prepared by dissolving the above formulation (1.0 g.) in 1 liter of 50 ppm hard water (calculated as two-third calcium carbonate and one-third magnesium carbonate). The low detergency standard (Control A) contained the formulation (1.0 g.) dissolved in one liter of 180 ppm water (same basis).

$$RDR = 2.2 + 4.1 \frac{\% SR_{Test} - \% SR_{Control\ A}}{\% SR_{Control\ B} - \% SR_{Control\ A}}$$

A further refinement in the determination of relative detergency ratings was developed. In this method, instead of employing two standard formulations, one of the formulations used as one of the four test solutions had a known relative detergency rating (RDR) which had been determined by the above formula. Relative detergency ratings of the other three formulations were then determined by comparing the percent soil removal (SR) of these formulations with that of the known formulation.

Detergency results obtained on a variety of the subject compounds are given in the following table. Each value shown is the average of at least four tests. For comparison, the detergency rating is given for a linear alkylbenzene sulfonate (LAS) (having from 10 to 13 carbon straight chain alkyl groups) both with and without phosphate builder (sodium tripolyphosphate).

Each formulation tested comprised 25 weight percent of the test material along with 1% carboxymethylcellulose, 7% sodium silicate, 8% water, and sufficient sodium sulfate to make 100%. The LAS comparison formulations were prepared in the same way except that in Test 1 20% of LAS and 35% of sodium tripolyphosphate were used. The formulations were tested at a concentration in water of 0.10 and 0.15 weight percent. The test results were obtained at a pH of 9.5.

As can be seen from these data, the compositions of this invention are highly effective as heavy duty laundering agents. Their effectiveness is comparable to conventional LAS with phosphate and surprisingly more effective than LAS without phosphate builders.

In order to determine the tolerance of fish for the detergent active compounds of this invention the following routine bioassay method was employed: "Standard Methods for the Examination of Water and Waste

Water", American Public Health Association, pages 458-471, 11th Edition (1960). The test is performed as follows: For each test concentration a 5-gallon jar containing 10 liters of tap water dechlorinated by air blow-

tration with more than 50% survival and the lowest concentration with less than 50% survival.

It was found in these tests that those compounds having central attachment of the succinic ester portion of the molecule to the hydrocarbyl chain were surprisingly less toxic than the compounds having end chain attachment. Table III contains data comparing the toxicity of compounds having central and end chain attachments.

ing was prepared. The test surfactant is added and 10 sticklebacks (Gasterosteidae) are transferred from a fresh water holding tank to the jar. Dead fish are counted and removed at 6 hours, 24 hours, 48 hours, 72 hours and 96 hours. The test concentrations are based on decilog intervals, and the 96-hour median tolerance limit (TL_m⁹⁶) is obtained for graphical or arithmetic interpolation between the highest concen-

65 These data show that the TL_m⁹⁶ values for most of the compounds of this invention, particularly those having internal attachment are surprisingly higher than the linear alkylbenzene sulfonate.

The degree of degradation under conditions such as are encountered in cesspools and septic tanks for the compounds of this invention were determined by tests set forth in "Microaerophilic Biodegradation of Tal-

low-Based Anionic Detergents in River Water", E. W. Maurer, T. C. Crodon, and A. J. Stirton, The Utilization Res. Dev. Div., ARS, USDA, Philadelphia, Pennsylvania, JAOCs, Volume 48, Page 163 (1971). The microaerophilic test procedure described in this article was employed with the exception that a bacterial seed (10% of filtered primary sewage anaerobic digester mix) was employed, the test was operated at room temperature and, in contrast to the results obtained by the authors, a small amount of degradation was observed in each case for linear alkylbenzene sulfonate.

Data in the following table show the degradation performance of the compounds of this invention in this test. The amount of surfactant in percent remaining after 2, 3, 5 and 6 days determined by standard methylene blue analysis is set forth.

TABLE V

Compound	MICROAEROPHILIC TEST Percent Active Remaining After Elapsed Time			
	2 Days	3 Days	5 Days	6 Days
LAS	84	75	44	41
Product of Ex. No. 19	23	13	7	7

The sulfate-carboxylates of this invention may be employed in combination with other detergent active materials such as linear alkyl and alkenyl disulfates and disulfonates, straight chain primary alcohol sulfates, LAS, olefin sulfonates and soap.

In employing the detergent active materials of this invention in detergent compositions, they may be formulated with additional compatible ingredients being optionally incorporated to enhance the properties of the formulations. Such materials may include but are not limited to anticorrosion, antiredeposition, bleaching and sequestering agents, foam boosters, and certain organic and inorganic alkali metal and alkaline earth

metal salts such as inorganic sulfates, carbonates, or borates. Also nonphosphate builders may be included in the composition. Also small quantities of phosphate builders may be included in the compositions, although, of course, they are not necessary for effective detergency.

While the character of this invention has been described in detail with numerous examples, this has been done by way of illustration only and without limitation of the invention. It will be apparent to those skilled in the art that modifications and variations of the illustrative examples may be made in the practice of the invention within the scope of the following claims.

We claim:

1. A surface active compound of the formula

in which R_1 and R_2 are substantially linear alkyl or alkenyl groups of 3 to 19 carbon atoms, R_3 is alkylene of 2 to 4 carbon atoms, u , v , x and y are 0 or 1, z is an integer 1 to 4, M is H or an alkali metal, alkaline earth metal, or ammonium cation, the sum of the carbon atoms in R_1 and R_2 is 13 to 21, the sum of the unsaturated sites in R_1 and R_2 is 1, the sum of u and v is 1, the sum of x and y is 1, and the sum of u and x is 1.

2. The compound of claim 1 in which the sum of the carbon atoms in R_1 and R_2 is from 15 to 17.

3. The compound of claim 1 in which M is alkali metal.

4. The compound of claim 3 in which M is sodium.
